CLAIM

The ornamental design for a decorative split hinge for sectional garage doors, as shown and described.

DESCRIPTION

FIG. 1 is a front perspective view of a plurality of decorative split hinges according to the invention mounted to a three section garage door, which is shown in phantom;

FIG. 2 is a perspective view of a single split hinge according to the invention;

FIG. 3 is a front elevation view of the single split hinge shown in FIG. 2;

FIG. 4 is a right side elevation view of the single split hinge shown in FIG. 2;

FIG. 5 is a left side elevation view of the single split hinge shown in FIG. 2;

FIG. 6 is a top plan view of the single split hinge shown in FIG. 2; and,

FIG. 7 is a bottom plan view of the decorative split hinge for sectional garage doors shown in FIG. 2.

The broken lines depicting garage door sections, and the various components thereof, represent environmental elements only, and form no part of the claimed design.
